PAIR OF SPECTACLES

Robert H. Ramp, Pittsford, N.Y., assignor to Bausch & Lomb Incorporated, Rochester, N.Y., a corporation of New York

Filed May 10, 1967, Ser. No. 7,058

Term of patent 14 years

(Cl. D57—1)

FIG. 1

FIG. 2

FIG. 3

FIG. 1 is a front view of a pair of spectacles showing my new design;

FIG. 2 is a side view of said pair of spectacles taken from the left side as viewed in FIG. 1; and

FIG. 3 is a top view thereof.

The side not shown has substantially the same appearance as the side shown.

The temples are broken away in FIG. 3 for convenience of illustration.

The dominant features of my design reside in those portions shown in solid lines, being characterized by the overhanging portions at the top of the lens-holding members having the configuration as shown, and in association with the remaining features thereof.

I claim:

The ornamental design for a pair of spectacles, substantially as shown and described.
